UNITED STATES PATENT OFFICE.

HERBERT A. WRENN, OF WASHINGTON, DISTRICT OF COLUMBIA, ASSIGNOR TO THE WRENN ADDING MACHINE COMPANY, OF WASHINGTON, DISTRICT OF COLUMBIA, A CORPORATION OF DISTRICT OF COLUMBIA.

CALCULATOR.

1,341,962.

Specification of Letters Patent.

Patented June 1, 1920.

Application filed April 4, 1917, Serial No. 159,696. Renewed December 24, 1919. Serial No. 347,195.

To all whom it may concern:

Be it known that I, HERBERT A. WRENN, a citizen of the United States, and a resident of Washington, in the District of Columbia, have invented a new and useful Improvement in Calculators, of which the following is a specification.

My present invention relates generally to calculators and consists more particularly in certain improvements over and in connection with my Patent, No. 1,181,819, dated May 2, 1916.

The primary object of my present improvement is to provide means in connection with the well known chain type of calculators, whereby to effectively prevent overrunning either in the manipulation of the chains in use or the resetting of the series of number wheels, and a further object relates more particularly to improvements in the zero setting mechanism.

Still further objects relating for the most part to details of construction to be herein-after more fully described, will be better understood from the following description of the construction, arrangement and operation of the several parts, reference being had to the accompanying drawings, forming a part of this application, and wherein—

Figure 1 is a front elevation of my improved calculator, partly broken away and in section,

Fig. 2 is a vertical transverse section taken substantially on line 2—2 of Fig. 1.

Fig. 3 is a detail perspective view of one of the transfer levers.

Fig. 4 is a detail perspective view of one of the chain locking plates,

Fig. 5 is a detail horizontal section taken substantially on line 5—5 of Fig. 1.

Fig. 6 is an enlarged sectional view corresponding to the lower portion of Fig. 2,

Figs. 7 and 8 are vertical sections taken on line 8—8 of Fig. 1, illustrating two positions of one of the number wheels, in connection with portions of the transfer mechanism,

Fig. 9 is a sectional view along a similar line looking in the opposite direction,

Fig. 10 is a detail perspective view of a portion of one of the chains,

Figs. 11 and 12 are respectively a side

and plan view of the spring stop for the zero setting lever.

Referring now to these figures my present improvements are utilized in connection with a calculator including a supporting frame 15 mounted with a casing 16 and the side portions of which frame are connected at the front of the machine by an upwardly and rearwardly inclined keyboard having the vertically projecting series of horizontally spaced guides 17, certain of which are seen particularly in Fig. 5, the guides 17 forming between them channels in which the chains 18 travel, and the keyboard as seen particularly at 19 in Fig. 5 having recesses in the bases of the channels between the guides 17 into which the numbered strips 20 are disposed either with or without protecting coverings 21 of glass, mica or other suitable transparent or translucent material.

The casing 16 has a front opening exposing the major portion of the surface of the keyboard and has upper and lower front wall sections 22 and 23, as seen in Figs. 1 and 2, the upper section 22 of which is provided with a series of horizontally aligned and spaced openings 24 in alignment with the channels between the several guides 17 of the keyboard, and the lower section 23 of which is provided with an upper edge 25 adjacent the lower portion of the keyboard, which forms a permanent rigid stop for the operator's fingers working downwardly in the channels of the keyboard in the operation of the machine as presently described.

Mounted through the upper portions of the side walls of the frame 15 is a shaft 26 on which are a series of number wheels 27 equal in number to the openings 24 of the casing and the channels of the keyboard, each of said wheels having a tooth-like numbered peripheral surface, the grooves 28 between the numbered facets of which receive the cross bars 29 of the links of the respective chain 18, the chain passing upwardly around the number wheel as seen particularly in Fig. 2 and as well known in this type of calculator.

Thus the upper run of each chain extends into its respective guide channel of the keyboard 19 while the lower run passes rearwardly of the keyboard as seen particularly

in Fig. 2, the lower end of the chain passing around a cross bar 30 secured through the upper free ends of the extensions 31 of a U-shaped tension member, the lower cross bar 32 of which is engaged by the forward hook end of a spring 33, the latter anchored to a stationary cross bar 34 of the frame 15.

Each of the extensions 31 of each tension member has a V-shaped notch in its rear edge adjacent the cross bar 32 for the reception of the forward downwardly inclined knife edge 35 of a bearing cross bar 36, which permits the tension member to yield on the bearing thus formed without undue friction as each link of its respective chain 18 passes therearound, as plainly seen by a comparison of Figs. 2 and 6, such movement of course being under tension of the spring 33.

It is understood, of course, that the tension members extend in a series aligned with the several operating chains 18 and that the numbered facets of the number wheels 27 are arranged to show through the openings 24 of the casing so that by placing his finger upon that cross bar of the chain 18 in one of the channels immediately below the desired number in the base of the channel, the operator by then moving his finger downwardly until further motion is arrested by the stop 25, may turn the respective number wheel to show the desired number through the respective sight opening 24.

In starting operation with the several number wheels in the zero position shown in Fig. 1, the first channel at the right hand side is utilized unless a number consisting of more than one figure is to be registered.

The transfer mechanism includes a cross rod 37 at the rear of and parallel with the shaft 26 on which are pivoted at their rear ends a plurality of transfer arms 38, these arms being positioned between the several number wheels 27 and provided at one side with intermediate laterally projecting rollers 39, the forward extremities of these arms being pivotally connected to the upper extremities of forwardly and downwardly inclined transfer levers 40, depending in a series in spaced relation beneath the keyboard 19, with their lower offset ends 41 working through a transverse guide bar 42 and provided with upwardly inclined lower angular extremities 43, the lower extremity of each lever being thus positioned in vertical alignment with the lower portion of the chain 18 of the next adjacent number wheel to the left thereof.

Each of the number wheels 27 has at its left side a laterally projecting cam 44, which in the rotation of the number wheel in operation works against the roller 39 of its respective transfer arm 38 to gradually lift the same a distance equal to the length

of one link of its respective operating chain 18, the cam 44 having an end shoulder 45 which permits the roller 39 and the respective arm 38 to drop when the end of the cam is reached and provide for lowering movement of the respective transfer lever 40, the lower angular extension 43 of which operates against that cross bar of its respective operating chain 18, previous to which it has been elevated above, to thus force the chain downwardly and rotate the corresponding number wheel a single space. To this end each transfer lever 40 is engaged at an intermediate point by the upper end of a spring 46 the lower end of which is anchored to the guide bar 42 before mentioned.

Referring to Figs. 7 and 8 it will be noted that each number wheel 27 is provided with a laterally projecting pin 47 spaced from the upper portion of the cam shoulder 45 a distance just sufficient to admit of the passage of the respective roller 39 between these parts, the pin being thus positioned for engagement by the roller as the latter moves over the end of the cam so as to thus promptly and effectively check further movement of the respective number wheel and obviate the danger of overrunning in the operation of the zero mechanism to be presently described.

In constructing the apparatus the first number wheel at the right is preferably set slightly in advance of the others in respect to its direction of rotation in order to provide for the release of the parts operating the next adjacent number wheel of the series, slightly in advance of all others, in the zero setting operation in the interest of which an operating handle 48 is provided as best seen in Fig. 1, having a socket portion 49 extending through an opening in one side of the casing 16 and engaging the adjacent end of the shaft 26 whereby rotation of the handle will impart similar rotation to the shaft.

Each of the number wheels 27 has a hub portion 50 loosely disposed on the shaft 26 as best seen in Fig. 9 and is further provided with a radial spring arm 51 anchored thereto at the outer end of the arm, the inner end of which projects through a slot 52 of the hub 50 for engagement with the periphery of the shaft 26. Adjacent each of the wheels the shaft is cut away to form a shoulder 53 over which the end of the spring 51 freely passes in the normal rotation of the number wheel in the direction indicated by the arrow in Fig. 9, at the same time providing for engagement of the shoulder with the inner end of the spring arm 51, when the shaft is rotated in the same direction by the zero setting handle 48.

Thus by the complete rotation of the handle 48 from its normal position, all of

the number wheels will be reset to the zero position as shown in Fig. 1.

In order to prevent movement of the handle 48 beyond the full stroke whereby 5 to prevent overrunning of the shaft 26, a spring stop preferably of the form shown in Figs. 11 and 12 is utilized attached to the adjacent side wall of the casing 16, this spring stop including an upwardly projecting 10 spring arm 54 having a cam shaped head 55 which, in the movement of the lever 48 toward the stop in the direction of the arrow of Fig. 11 is engaged by a laterally projecting pin 56 of the said lever to move 15 the spring arm 54 to the position shown in dotted lines in Fig. 11. The arm 54 has a horizontal angular stop piece 57 below its head 55 into engagement with which the pin 56 moves when the arm 54 is in the 20 dotted line position of Fig. 11, so as to prevent further downward movement of the lever, the pin 56 being then in the position shown in dotted lines at 56^a in Fig. 11, and the arm 54 being prevented from return 25 movement from its position shown in dotted lines in Fig. 11 by virtue of a shoulder 58 above which the lever pin 56 must be subsequently elevated. When the pin is elevated the spring arm 54 will return to the 30 normal position in full lines in Fig. 11 and the lever will then be free for subsequent movement in the next zero setting operation in the proper direction, its movement in the reverse direction being prevented by 35 a lug 59 of the spring arm 54.

It is obvious that in the operation of a calculator of the present type a hurried or 40 jerky motion of the operator's fingers, even though limited to some extent by the stop 45 25 of the casing, is calculated to bring about overrunning of the operating chains at times, and thus overrunning of the number wheels, a disadvantage which I seek to overcome by the provision of means capable of movement adjacent the stop 25 in normal 50 operation and which, upon engagement by the operator's fingers, will effectively lock the chains against further movement and thus against overrunning.

I therefore provide an upwardly and rearwardly inclined locking plate 60 as shown 55 in Fig. 4 having its upper angular end 61 extending into the lower open end of the respective guide channel of the keyboard 19, and provided at its lower end with depending side arms 62, the lower extremities of 60 which are pivotally mounted upon the projecting extremities of the cross rod 30 of the respective tension member 31 before described, so that as each link of the respective operating chain, in its movement around the cross rod 30, rocks the respective tension member 31, the respective locking plate 60 will be elevated to thrust its upper angular 65 end 61, normally flush with the stop 25, as

shown in Fig. 2, to a point above the said stop as shown in Fig. 6. Thus as each cross bar of each of the chains reaches the stop 25, the respective stop plate 60 will be in course of elevation, and upon being engaged 70 by the operator's finger, will lock the tension member, and in this manner act as an effective check against further and overrunning movement of the respective operating chain.

It is thus obvious from the foregoing that 75 my invention provides a calculator of the present type capable of a generally more effective and more efficient operation in uses to which such an apparatus is generally assigned, and that my improvements in each 80 instance materially contribute to greater usefulness and capabilities without adding materially to the constructive cost thereof and without unduly complicating the same.

I claim:—

1. A calculating apparatus of the character described including a keyboard, a series of number wheels above the keyboard, link operating chains, the upper runs of which extend over the keyboard and which project 90 around the number wheels at their upper ends, tension members at the lower ends of the chains, each of said tension members including a pivoted U-shaped piece, the free ends of which are connected by a rod around 95 which the lower end of the respective chain passes, springs engaging the cross bars of said U-shaped tension members, and locking plates adjacent the lower end of the keyboard pivotally connected to the said tension 100 members and vertically shiftable upon rocking movements of the said tension members, for the purpose described.

2. A calculating apparatus of the character described including a keyboard, a series 105 of number wheels above the keyboard, link operating chains, the upper runs of which extend over the keyboard and which project around the number wheels at their upper ends, tension members at the lower ends of 110 the chains, each of said tension members including a pivoted U-shaped piece, the free ends of which are connected by a rod around which the lower end of the respective chain passes, springs engaging the cross bars of 115 said U-shaped tension members, and locking plates adjacent the lower end of the keyboard pivotally connected to the said tension members and vertically shiftable upon rocking movements of the said tension members, 120 said locking plates having the upper angular finger engaging ends and provided with depending side extensions having apertures at their lower ends receiving the extremities of the cross rods of the tension members. 125

3. A calculating apparatus of the character described comprising a keyboard, a series of number wheels at the upper end of the keyboard, link operating chains extending over the keyboard and at their upper 130

ends around the said number wheels, tension members engaging said chains at their lower ends and vertically shiftable locking members operating adjacent the lower end of 5 the keyboard and connected to, and shiftable vertically by, the said tension members.

4. A calculating apparatus of the character described having a keyboard provided with channels, finger actuated chains movable in said channels, number wheels at the 10 upper end of the keyboard around which the upper ends of the chains travel, tension members around portions of which the lower ends of said chains extend, and locking members for checking movement of the 15 chains consisting of plates adjacent the lower end of the keyboard having upper angular ends extending into the lower ends of the said channels of the keyboard and 20 connected at their lower ends to and shiftable by the said tension members.

5. A calculating apparatus of the character described having a keyboard, a series of 25 number wheels, link operating chains extending over the keyboard and around said number wheels at one end, tension members engaging said chains at their opposite ends and means connected to said tension members and manually actuated to check movement of said chains.

6. In an apparatus of the character described the combination of operating chains, a keyboard on which the said chains operate having a finger stop and manually actuated means adjacent the finger stop for 35 checking movement of the chains.

7. In an apparatus of the character described the combination of operating chains, a keyboard on which the said chains operate 40 having a finger stop and manually actuated means adjacent the finger stop for checking movement of the chains, said means consisting of vertically shiftable locking members normally moved by the chains.

8. In an apparatus of the character described, the combination of a keyboard having a lower finger stop, number wheels, operating chains extending over the keyboard and around the number wheels, means to 45 tension the said chains, and means to prevent overrunning of the chains in use consisting of members arranged adjacent the said finger stop and vertically reciprocated during normal movement of the said chains, 55 whereby pressure upon the said members will check movement of the said chains.

9. In a calculator of the type described, a series of number wheels, a series of operating chains extending at one end around 60 said number wheels and tension members at the opposite ends of said chains including U-shaped pieces having their extensions provided with intermediate V-shaped recesses, a cross bar connecting the extensions of said members and around which the adjacent end

of the respective chain passes, and a cross bar forming a bearing for said tension members and having a knife edge extending into the V-shaped recesses of the said members.

10. In an apparatus of the character described, the combination of operating chains, a keyboard on which said chains operate, and manually controlled means adjacent the lower portion of the keyboard for checking movement of the chains. 70

11. In an apparatus of the character described, the combination of operating chains, a keyboard on which said chains operate, and a finger engaging member for each chain for checking movement thereof, arranged in the path of movement of the chain. 80

12. In an apparatus of the character described, a calculating mechanism including operating members movable during operation, and stop members adjacent said operating members and moved thereby during movement of the operating members, whereby by checking of movement of the stop members will check the operating members and 90 prevent their overrunning.

13. In an apparatus of the character described, the combination of an endless movable operating member and a manually controlled stop member normally moved by the 95 operating member and disposed adjacent to the path of movement thereof.

14. In apparatus of the character described, the combination with a totalizer, of a movable endless belt operating member 100 therefor, adapted to be shifted by the finger of the operator or by a stylus held in the hand of the operator, and means to hold the endless belt operating member against overrunning movement, said means being arranged near the endless belt operating member to be actuated by the finger or stylus which is employed to move the endless belt operating member. 105

15. In apparatus of the character described, the combination with a totalizer, of a movable operating member therefor, adapted to be shifted longitudinally by the finger of the operator or a stylus held in the hand of the operator, and means to prevent 115 over-running movement of the movable operating member, including an element arranged near and upon one side of the movable operating member to be thereby disposed in the path of travel of the finger or 120 stylus and to be actuated by the said finger or stylus serving to move the movable operating member.

16. In a device of the type described an indicia bearing member, an operating member therefor adapted to be operated by the finger or a stylus held in the hand of the operator, means adjacent said operating member and operatively connected with said indicia bearing member and adapted to be 125 130

operated by the finger or stylus simultaneously with the operating member whereby the indicia bearing member will be checked against movement.

- 5 17. In a device of the type described a rotating element, an operating member therefor adapted to be shifted longitudinally by the finger of the operator or a stylus held in the hand of the operator, and
10 means arranged in the path of travel of the finger or stylus for checking the rotation of said rotating element.

17. In a device of the type described a totalizer, an operating member therefor embodying a plurality of simultaneously shiftable elements adapted to be engaged by the finger of the operator or a stylus held in the hand of the operator, and means for locking

said operating member against movement in one direction when the operating member 20 has been shifted a predetermined distance.

19. In a device of the type described, a totalizer, an operating member therefor, embodying a member adapted to be shifted by the finger of the operator, or a stylus held in the hand of the operator, and means adjacent said operating member and operated simultaneously therewith when the operating member has been shifted a predetermined distance, for checking the motion of 30 said totalizer.
